SKI-BOARD

Craig A. Wood, 422 F St., Davis, Calif. 95616

Filed Oct. 14, 1971, Ser. No. 189,478

Term of patent 14 years

Int. Cl. D12—14

U.S. Cl. D12—9

FIG. 1.

FIG. 2.

FIG. 3.

FIG. 4.

FIG. 5

FIG. 6

FIG. 1 is a top plan view of a ski-board showing my new design;

FIG. 2 is a side elevational view thereof;

FIG. 3 is a bottom plan view thereof;

FIG. 4 is a top plan view of the ski-base portion, the upper body having been omitted for ease of illustration;

FIG. 5 is a side elevational view of another embodiment of my new design of FIG. 1 wherein fins have been substituted in place of the ski-base; and

FIG. 6 is a bottom plan view of FIG. 5.

I claim:

The ornamental design for ski-board, substantially as shown and described.
